UNITED STATES PATENT OFFICE.

IVAN W. GROTHEY, OF YORK, PENNSYLVANIA, ASSIGNOR TO GENERAL MACHINE WORKS, OF YORK, PENNSYLVANIA, A CORPORATION OF PENNSYLVANIA.

STOP-MOTION MECHANISM FOR KNITTING-MACHINES.

1,158,485.

Specification of Letters Patent.

Patented Nov. 2, 1915.

Application filed July 2, 1909. Serial No. 505,740.

To all whom it may concern:

Be it known that I, IVAN W. GROTHEY, a citizen of the United States, residing at York, in the county of York and State of Pennsylvania, have invented certain new and useful Improvements in Stop-Motion Mechanism for Knitting-Machines, of which the following is a specification.

In stop motion mechanism for knitting machines heretofore in common use it has ordinarily been necessary to mount the same on a suitable support at a considerable elevation above the top frame of the machine in order to guard against knitting the loose threads completely into the work before the mechanism can be stopped, and in some forms of such mechanism it has also been necessary to cut the threads to cause the stop motion mechanism to operate.

20 The purpose of my said invention is to provide a stop motion mechanism which will be principally mounted directly upon the top ring of the machine frame, thus bringing its principal weight to a point 25 where its vibration will not cause undue strain upon the machine and also provide such a mechanism which will operate under any unusual strain upon the threads, or yarn, whether causing said yarn to break or 30 not, and also a mechanism which will operate to stop the machine almost instantaneously, and it consists in various improvements in the construction and arrangement of parts whereby these purposes are 35 accomplished, all as will be hereinafter more fully described and claimed.

Referring to the accompanying drawings which are made a part hereof and on which similar reference characters indicate similar 40 parts, Figure 1 is a perspective view showing the top portion of a knitting machine looking at the same from the rear side, provided with my stop motion mechanism. Fig. 2 a rear elevation of the parts constituting 45 the stop motion mechanism on an enlarged scale with a portion of the standard broken away, Fig. 3 a top or plan view of the lower portion of the stop motion mechanism, Fig. 4 a side elevation of the upper part of said stop 50 motion mechanism, Fig. 5 a side elevation of the lower part of said stop motion mechanism, Fig. 6 a vertical section through the same on the dotted line 6—6 in Fig. 3, Figs. 7, 8, 9, 10, 11, 12 and 13 detail views of various parts of the mechanism on an enlarged 55

scale, and Figs. 14, 15, 16, 17 and 18 views similar to Figs. 1, 2, 3, 5 and 6, but showing a modification in the construction.

In said drawings the portions marked A represent the frame of the machine and B 60 the casing inclosing the trip devices of the stop motion mechanism.

The knitting machine illustrated is a circular knitting machine of well known construction, designed principally for knitting 65 stockings, etc., and requires no detail description, being shown merely to illustrate the use of my said invention, which is equally adapted for use on knitting machines of any other type for which it may 70 be found suitable.

The frame A is preferably a casting comprising an upper and lower ring connected by side pieces and adapted to support the various parts of the mechanism as shown. 75 The casing B is a hollow casting formed of a base plate B' having downwardly projecting ears b formed on the arc of a circle adapted to fit upon the rear edge of the top ring of the frame A, to which it is secured 80 by screw-bolts b'. Its front side is formed open and provided with a cover plate B² secured thereon by screws b². Across the front end of its top side is formed a section in piece therewith on the top of which is 85 formed a boss B³ containing a socket b³ to receive the lower end of post 60 on the upper end of which are mounted other parts of the mechanism.

A rock-shaft 20 is journaled in bearings 90 formed in ears b⁴ which are formed on the top face of the base-plate B' near each end thereof. Said rock-shaft 20 also extends through the casing B near its front end. A strong coiled spring 21 is mounted on said 95 rock-shaft near one end, one end of said spring being secured to said rock-shaft on a pin 22 and its opposite end 23 hooked over the rear edge of plate B'. An arm 25 is rigidly secured on shaft 20 inside of casing 100 B by means of a pin 24 which extends through a perforation in said arm and said rock-shaft. A lever 26, carrying a spring catch 27, is mounted on a horizontal pivot 28 which extends from one side to the other 105 of said casing B near the bottom thereof. A spring 29 mounted on said pivot 28 with one end bearing on the bottom of said casing and the other end bearing on the rear face of 110 said lever, tends to throw the upper end of

said lever forward on its pivot toward rock-shaft 20. The catch 27 is mounted and adapted to slide in a perforation through said lever, being carried on the lower end of 5 a leaf-spring 30 the upper end of which is secured to the backside of said lever near its upper end by rivets or screws 8. The outer end of arm 25 is formed with a projecting finger 31 with a curved lower corner said finger being adapted to engage under said catch 27 when in the position shown by whole lines in Fig. 6. Said lever 26 has a 10 forwardly projecting arm 32 on its upper end of the form best shown in Fig. 7, with a 15 projecting ear 33 on one side. A trip lever 35, of the form best shown in Fig. 8, is mounted on a horizontal pivot 36, being formed of two horizontal members connected at their rear ends, one of said members 20 being formed with a notch 37 in its top edge with which the ear 33 of the arm 32 on the upper end of lever 26 is adapted to engage. A spring 38 is bent around said pivot 36 and one end extends out horizontally and 25 engages with a perforation, or notch, in the side of casing B, while its other end engages under a projection, as pin 39 in the side of said lever, said spring thus serving to normally hold the rear end of said lever upward and maintaining the notch 37 and ear 33 in engagement. A plate or lever 40 is mounted on a horizontal pivot 41 extending between suitable ears on the top of casing B and is provided with an arm 42 which extends down through an aperture in the top 30 of said casing and is adapted to strike upon the rear end of said lever 35.

Horizontal tubes or hollow arms 45 and 46 extend outwardly from each side of the 40 casing B near its rear top corners, being preferably threaded at their inner ends and screwed into screw-threaded perforations provided therefor in the sides of said casing. Rods 47 extend through said arms projecting at their inner ends into the interior of the casing said inner ends being bent to form angularly extending arms 48 which are positioned immediately above the rear end of lever 35 and adjacent to each side of 45 the lower end of arm 42. On the outer end of each of the tubes 45 and 46 is mounted an upwardly extending rigid arm 50 near the top end of which are provided horizontally projecting fingers 51 and 52. The outer end 50 of each rod 47 extends beyond the outer end of its inclosing tube and an arm 53 preferably formed of wire, is mounted therein and so connected to said rod as to swing therewith. On the upper end of each of said arms 53 are formed horizontal fingers 54 and 55 one of which is adapted to be positioned between the fingers 51 and 52 of the arms 50 and the other of which is adjacent to the lower one of said fingers. Said arms 53 are 60 supported in a vertical position by the 65

threads from the spools of yarn, which passes between their fingers and the fingers of arms 50. See Fig. 2. When either one of said arms 53 falls down into a horizontal position from any cause, such as the breaking or cutting of a thread, the bent inner end 48 will contact with the rear end of lever 35 and throw it downwardly on its pivot, releasing the notch 37 from the ear 33 of lever 26. 70

A standard 60 is mounted in socket b^3 of the boss B^3 on the front end of the top of casing B and extends upwardly a suitable distance and carries an arm 61 on its upper end the lower end or base of said arm 61 being formed with a vertical socket adapted to fit over the top end of said standard. Said arm 61 extends a sufficient distance to one side of the standard 60 to carry the threads to a suitable position over the knitting mechanism. A brace rod 62 is secured at its upper end in the backside of the base of arm 61 and extends down through a distance piece 63, mounted in an intermediate position on standard 60, into a socket in a 80 boss B^5 on the rear edge of the base plate B' of the casing B, where it is secured by a set screw b^5 , thus bracing and supporting said standard. Yarn or thread supporting arms 65 and 66 are mounted at their lower 85 ends in normally vertical sockets 67 and 68, which sockets are provided on the upper ends of levers 69 and 70, which are mounted on horizontal pivots 71 and 72, respectively, on opposite sides of the base of arm 61. An angle lever 73 is mounted on a pivot 74 on 90 said base its lower end carrying a pin 75 extending through said arm and to each side thereof a sufficient distance to rest upon the rear edges of the levers 69 and 70, so that the operation of either lever 69 or 70 will 95 throw the lower end of said lever 73 outwardly and its horizontal part upwardly. The outer end of the horizontal part of said lever 73 is connected by a rod 76 with the forward end of plate 40 pivoted on the top 100 of casing B. On each side of the outer end of arm 61 are mounted rocking disks 80 and 81 respectively, each of which is formed with a tapered edge at its upper forward 105 side, on each side of which are mounted forwardly extending fingers 82 and 83, finger 82 being on the outside of the disks and normally extending at a slight angle above a horizontal direction. Connecting rods 84 and 85 connect the lower side of each of 110 said disks with the lower ends of the levers 69 and 70, respectively, so that any swing of said levers also serves to oscillate said disks. Said arms 69 and 70, as before described, 115 carry the yarn-supporting arms 65 and 66 swiveled in sockets on their upper ends and just above said sockets each of said yarn supporting arms is formed with a horizontal arm 65^a and 66^a, respectively, which arms 120

125

are adapted to rest against the rear face of the base of said arm 61. Coiled springs 86 and 87, respectively, are mounted on the lower ends of said arms 65 and 66 below the 5 sockets, one end of each of said springs being connected with the lower end of its arm and the other connected with the socket in which it swivels, so as to normally hold said arms in the position shown in Figs. 2 and 4 with the arms 65^a and 66^a resting in a transverse position against the rear face of the base of arm 61. The tops of the levers 69 and 70, respectively, are connected by springs 88 and 89 to the upper ends of 10 levers 90 and 91, which are mounted on a pivot 92 in the brace rod 62. Said levers 90 and 91 are each angle levers and their lower ends are pivoted to adjusting screws 93 and 94 which project through suitable perforations in the ends of a cross arm 95 on brace 15 62 and are provided with thumb nuts 96 and 97, respectively, by which they may be adjusted and the tension of the springs 88 and 89 regulated. It will thus be seen that 20 said springs 88 and 89 normally hold the thread supporting arms 65 and 66 in a vertical position and with their arms 65^a and 66^a in a position parallel with the rear face of the base of the arm 61.

25 The main driving shaft of the machine 100 is geared to the various mechanisms in the usual or any approved manner. It is provided with a hand-wheel 101 by which it may be turned by hand to bring the mechanism to any desired position. It is provided with an idler pulley 102 and a driving pulley 103 alongside said idler pulley by which it may be driven from any suitable or convenient power. It is also provided with 30 a brake pulley or wheel 104 which is surrounded by a band-brake 105 the two ends of which are connected to adjacent pins projecting from the side of a lever 106, which is pivoted on a pivot 107 to a suitable bracket 108 bolted to the top of the machine frame. The pins to which the ends of said band-brake 105 are pivotally connected project from the lever on opposite sides of its pivot, as shown clearly in Fig. 1, 35 so that as said lever is rocked on its pivot the ends of said band-brake are moved to contract or expand the band and impinge or release the brake-wheel 104, as will be readily understood.

40 A belt shifter is provided, consisting of parallel prongs 10 adapted to straddle the belt, not shown, mounted on an arm 11 carried on bracket 12 which in turn is mounted on a slide rod 13 mounted to slide in a suitable bearing in a boss 5 formed on the side 45 piece of the frame A of the machine. A coiled spring 9 is mounted between said bracket 12 and the outer end of boss 5 which normally holds the belt shifter so as 50 to carry the belt on the idler pulley 102.

55 In the inner end of said sliding rod 13 is formed a notch n with which a latch 6 on pivoted lever 15 is adapted to engage. Said lever 15 is pivoted at 4 and a coiled spring 7 serves to hold it in a position to engage 60 the latch 6 with said notch n. A rod 16 is pivoted to the outer end of a crank arm 19 on rock shaft 20 and its lower end extends through a perforation in the outer end of lever 15 and adjustable collar 14 being 65 mounted on said rod above said lever to regulate the point of contact, as shown. Another crank arm 18 is mounted on the outer end of said rock shaft 20 and connected by a connecting rod 17 with lever 106 for operating the band-brake 105. Another lever 8 is pivoted on a bracket 3 on the side of the frame with its upper end engaging with the transverse pin or projection 2 on the side 70 of sliding rod 13, by which said sliding rod 80 may be thrown back to set the mechanism in operative position after the belt has been shifted and the brake set to stop the mechanism.

75 In operation, the machine is threaded as 80 shown in Fig. 1, the spool holder 110, of a common or any approved form, being mounted on the lower part of the frame of the machine and carrying the spools of yarn 111 and 112. The thread from spool 112 85 runs between the fingers 51 and 52 of the stationary arm 50 and the fingers 54 and 55 of the rocking arm 53, on the right-hand side, as indicated in said figure, then passes over a hook-shaped support on the top of 90 the yarn support 66, from thence over the periphery of the disk 80 and between the fingers 82 and 83 on the sides thereof, on the outer end of arm 61, and thence to the 95 needles in the knitting head. The thread from spool 111 passes in a similar manner from said spool through the fingers and supports on the left-hand side of the machine to the knitting head. When the machine is in operation, the mechanism inclosed by the casing B is set as shown in 100 Fig. 6, in which position the rock-shaft 20 and the crank arms 18 and 19 thereon are in the position shown in Fig. 1, the crank arm 18 being in position to hold the band-brake 105 loosely upon the periphery of the brake wheel 104 and the arm 19 being in position to permit the spring 7 to hold the lever 15 with the latch 6 ready for engagement 105 with the notch n in the underside of the sliding rod 13 and to hold the shifting-fork in position with the belt upon the driving wheel 103. In Fig. 1, however, the shifting-fork is adjacent to idler pulley 102 as lever 8 has not been thrown to slide rod 13 and parts carried thereby into position for 110 operation. In other words, the machine as illustrated in Fig. 1 is standing idle, with all parts ready to operate as soon as the belt 115 is shifted onto the driving pulley. The ma 120

125

130

chine being thrown into operation, with the parts so arranged and adjusted, and a break occurring in either one of the threads the finger 53 which was supported by the 5 thread broken will immediately fall down into a horizontal position so that its bent end or arm 48, on the inner end of the rod 47, will contact with the inner end of lever 35 throwing said lever downwardly and releasing its notch 37 from engagement with ear 33 of the lever 26. Immediately upon this engagement being broken the spring 21, which, when the parts are turned to the "set" position shown in Fig. 6, is under 10 powerful tension, acts through the contact between the part 31 of the arm 25 and the catch 27 to throw lever 26 backward and cause shaft 20 to make substantially a quarter turn bringing lever 25 to the position shown by dotted lines in Fig. 6. This motion of shaft 20 will throw crank arm 19 downwardly, bringing collar 14 into contact with the outer end of lever 15, forcing said lever downwardly, and disengaging the 15 latch 6 from the notch *n* in sliding rod 13, when the spring 9 will immediately cause said rod carrying the shifting-fork 10, to slide outwardly and shift the belt from the driving pulley 103 to the idler pulley 102. 20 At the same time the crank-arm 18 throws lever 106 backward upon its pivot closing the band-brake 105 tightly upon the periphery of the brake-wheel 104 and thus bringing driving shaft 100 to a sudden stop. Said 25 stop motion mechanism will also be set off by any knot, or imperfection, in either of the threads which passing through or over any of the thread-supporting parts causes an undue tension thereon, which will tilt forward 30 the top end of lever 69 or 70 carrying the yarn support 65 or 66, over which the thread is running, the yarn support being swiveled on its vertical pivot during said forward movement by means of contact of its horizontal portion with the rear face of the base 35 of arm 61. The upper end of said support is thus turned and tilted so that the hook thereon will point at an angle downwardly and permit the thread to slip off. The connecting rod 84 or 85, according to which 40 thread is in trouble, turns the disk 80 or 81 at the same time, which turns the outer prong 82 on said disk to an angle downwardly so that the thread will slide over the 45 tapered corner of the disk and said prong and fall off its support without breaking. At the same time the lower end of lever 69, or 70, will contact with the cross bar 75 of lever 73 throwing the horizontal arm 60 of said lever in an upward direction and through the connecting rod 76 tilt the lever-plate 40, which, through its arm 42, will throw the outer end of lever 35 downwardly, causing the same operation of the stop motion 65 mechanism as when set off by the fall-

ing of one of the arms 53 when a thread breaks, as before described.

When the operator has overcome the difficulty which caused the automatic stopping of the machine, the lever 106 is pulled forward, which, through its connection with shaft 20, rocks said shaft to throw lever 25 back into engagement under the spring catch 27 carried by the lever 26, the rounded corner of part 31 pressing upon the tapered top side of said catch serving to force it back by deflecting its supporting spring 30 as indicated by dotted lines in Fig. 6. Said levers 26 and 35 are held in normal position and relation at all times, except when forced out of such normal position, by means of the springs 29 and 38, respectively. After the mechanism in the casing B has thus been set the operator, through lever 8, slides the rod 13 carrying the belt shifting-fork 10 inwardly until the latch 6 on lever 15 engages with the notch *n* in the underside of said rod and locks said rod in this position, which brings the belt onto the driving pulley 103 and starts the machine into operation. As often as the yarn may break or any imperfection in the yarn, or other trouble, causes any abnormal tension, either in the feeding or the knitting, the stop motion mechanism will be automatically set off as 95 above described and the machine brought to an almost immediate stop before any harm can be accomplished or the threads knitted into the work. By adjusting the thumb-nuts 95 the degree of tension required upon the 100 threads to set off the stop motion mechanism may be regulated.

It will be noticed that all of the parts are so positioned and adjusted that the mechanism is very sensitive and will be operated 105 upon the slightest interference with the regular adjustment or operation of the machine and that the various movements of the several holding parts required to set off the stop motion mechanism are so slight 110 that the operation of shaft 20 under the power of the powerful spring 21 is substantially instantaneous and brings the mechanism to a stop before the knitting mechanism can use up any considerable length of 115 the thread after the interruption occurs.

In Figs. 14, 15, 16, and 17 I have illustrated a modification where using heavy yarn. In this arrangement the modification consists chiefly in the substitution of pivoted trip-levers 200 and 201, either of which is adapted to contact with and operate a plunger 202 to throw the lever 35 and set off the stop motion mechanism, for the devices carried on the top of standard 60 and 120 their connection with the plate 40, as shown in the principal views. Said levers 200 and 201 are pivoted between appropriate ears on the top of casing B and their rear ends are arranged to contact with the head of 125 130

plunger 202 when their forward ends are lifted up on their pivots. Each lever is formed with a notch in its top directly above its pivot in which the V-shaped lower end of a sliding plunger 203 is adapted to engage. Said detent is mounted in a vertical tube 204 in the top of which is mounted a thumb-screw 205 and between the end of said thumb-screw and the top of said plunger is mounted a coiled spring 206, so that by the adjustment of said thumb-screw the tension of the spring may be regulated to hold said detent into engagement with said notch with greater or less force as may be required to regulate the force necessary to operate lever 200 or 201. An upright 210 is mounted on the top of casing B and has transverse yarn supporting arms 211 and 212 extending each way therefrom and an 20 outwardly extending yarn supporting arm 213 curved over from the top thereof, suitable hooks being formed on the outer ends of each of said arms to receive and carry the threads. In this construction the thread 25 or yarn passes through between the horizontal fingers of the arms 50 and 53 of the lower part of the mechanism, as in the principal construction, then passes upwardly to the yarn supports 211 and 212, from thence down under thread receiving hooks formed on forward ends of levers 201 and 202, then up and over the yarn supports on the end 30 of arm 213 from thence down to the knitting mechanism.

As in the principal construction any break in the yarn will cause one or the other of the arms 53 to fall and set off the stop motion mechanism, which operates in identically the same manner as in the principal construction. Any undue tension upon either of the threads sufficient to exert the force required to lift the forward ends of levers 200 or 201 will raise said ends upwardly, causing their rear ends to press 45 downwardly upon the top of plunger 202, which will force the rear end of lever 35 downwardly and set off the mechanism with the same results as before described. It will be understood, of course, that these and 50 other modifications may be made in the details of construction without departing from the spirit of my said invention. I have thought it advisable to illustrate this second means of setting off the stop motion mechanism, by the tension of the threads, without breaking or cutting the thread, as I regard it as substantially the equivalent of the mechanism shown in the principal views 55 so far as the principal of operation is concerned. The construction shown in the principal views, however, permits the thread to be fed from the spool to the knitting mechanism without passing over so many parts and thus is more suitable for 60 delicate work where fine threads of a deli-

cate character are employed. The modified construction, however, will be found equally serviceable and practical, especially where the yarn employed is of the coarser variety and has sufficient strength to stand the 70 necessary strain and wear. By either form a stop motion mechanism is provided which may be mounted low on the machine, as well as the support for the yarn, relieving the machine of a great part of the usual vibration and reducing the necessary weight and strength of the frame, while at the same time bringing the parts into more convenient position for attention by the operator. Also one which will be set off and 75 operated entirely automatically either by the breaking of the yarn or by any abnormal strain upon the yarn caused by any imperfection in the thread, or any other cause, the two causes operating the mechanism entirely independent one of the other, and the latter cause not necessitating a break in the thread. Either form of device also is comparatively inexpensive to manufacture, light 80 in weight, and positive and almost instantaneous in operation.

Having thus fully described my said invention what I claim as new and desire to secure by Letters Patent, is:

1. A stop motion mechanism for knitting 95 machines comprising a sliding belt-shifter for shifting the driving belt of the machine, brake mechanism for stopping the driving shaft, a rock-shaft mounted under tension and directly connected to positively release 100 the means for actuating the belt-shifter and also connected to the brake mechanism to directly and positively operate the same, means for applying tension to said rock-shaft and actuating it, said means for actuating the belt-shifter, devices connected with said rock-shaft for holding it in set position as when the machine is in operation, and means for releasing said holding devices controlled by the threads in their passage 105 from the spools to the knitting mechanism, substantially as set forth.

2. A stop motion mechanism for knitting machines comprising a casing mounted directly on the base of the knitting head, 115 a spring-mounted rock-shaft extending through said casing, locking devices within said casing for holding said rock-shaft against the tension of its spring, crank-arms on said rock-shaft operatively connected respectively with the brake and the power controlling devices for actuating them, tripping devices for setting off the holding mechanism, and means for actuating said tripping devices controlled by the tension 120 of the threads, substantially as set forth.

3. A stop motion mechanism for knitting machines comprising a casing mounted on the base of the knitting head, a rock-shaft mounted under tension therein, means for 130

applying tension to said rock-shaft and actuating it, means for holding said rock-shaft against its tension while the machine is in operation, crank-arms on said rock-shaft operatively connected to the brake and power controlling mechanism respectively, a rod mounted to rock in a suitable bearing carried by said casing with its inner end formed to contact with the holding means and set it off when in one position and provided with an arm on its outer end through which the position of its inner end is controlled by the thread, substantially as set forth.

15 4. A stop motion mechanism for knitting machines comprising a casing on the base of the knitting head, a horizontal rock-shaft journaled in and mounted to extend through said casing, means connected with said rock-shaft for holding it under a tension in one direction, means mounted in said casing for holding said rock-shaft against said tension, operative connections running from said rock-shaft to the brake mechanism and 20 power controlling mechanism, respectively, and means for releasing the devices for holding said rock-shaft controlled by the thread in its passage from the spools to the knitting mechanism, substantially as set forth.

5. A stop motion mechanism for knitting machines comprising power controlling mechanism, brake mechanism, a casing mounted on the machine frame, a rock-shaft 35 extending through said casing, means for applying tension to said rock-shaft and actuating it, connections running from said rock-shaft to the power controlling mechanism and the brake mechanism, respectively, 40 thread guiding fingers carried on the outer end of horizontal arms extending laterally from said casing, rods extending through said arms to within said casing and provided with tripping fingers on their inner 45 ends and with arms on their outer ends having fingers adapted to extend adjacent to the fingers of said other arms and be held in position by the threads passing between said several fingers, whereby when the threads 50 break said arms will fall and rock said rods to bring their inner ends into contact with the trip mechanism for setting it off, substantially as set forth.

6. A stop motion mechanism for knitting machines comprising power controlling mechanism, brake mechanism, a rock-shaft, means for applying tension to said rock-shaft and actuating it, connections running from said rock-shaft to the power controlling mechanism and the brake mechanism, respectively, a radially extending arm fixed 60 on said rock-shaft within said casing and formed with an engaging shoulder on its outer end, a pivoted catch adapted to engage with said outer end to hold said rock

shaft under tension, means for normally holding said parts in engaged position, horizontal arms extending each way from said casing carrying vertical stationary arms with horizontally projecting fingers on their upper ends, rods mounted in said arms adapted to rock having arms on their outer ends adjacent to said stationary arms and formed with fingers adapted to come into position adjacent to the fingers of said stationary arms when said arms are parallel, the inner ends of said rods being bent to contact with the holding devices to trip the same when brought into contact therewith, said holding devices and means above said arms for supporting the threads in their passage from the spool to the knitting mechanism, whereby said thread may pass between the horizontal fingers of said arms and support the rocking arms in a position parallel with said stationary arms and the breaking of the threads will permit said rocking arms to fall to set off the holding devices and operate the stop motion mechanism, substantially as set forth.

7. A stop motion mechanism for knitting machines comprising brake mechanism, power controlling mechanism, a casing, a rock-shaft held under tension therein and connected with the brake mechanism and the power controlling mechanism, means for applying tension to said rock-shaft and actuating it, said rock-shaft being provided with a radial arm within said casing having a shoulder in its outer end for engagement with holding devices, a pivoted catch for engagement with said shoulder, a pivoted lever for holding said pivoted catch in engagement, means for actuating said lever and releasing said holding devices comprising a swinging arm mounted on a rod, said arm being arranged to be held in position to hold its inner end out of contact with said lever by the yarn when in operative position and to fall so that its inner end will contact with said lever to set off said holding mechanism when the yarn separates, substantially as set forth.

8. A stop motion mechanism for knitting machines comprising power controlling and brake mechanisms, a casing, a rock-shaft provided with cranks connected to the power controlling and brake mechanisms, holding devices for holding said rock-shaft under tension, means for applying tension to said rock-shaft and actuating it, means for setting off said holding devices comprising swinging thread supports mounted above said casing and arranged to be operated by any abnormal tension on the thread, a trip lever mounted on said casing for operating the holding devices therein, another lever pivoted adjacent to said thread supports and adapted to be operated thereby, and a connection running between said two levers,

whereby the swinging of said thread supports will release said holding devices and set off the stop motion mechanism, substantially as set forth.

5 9. A stop motion mechanism for knitting machines comprising a casing mounted on the base of the knitting head, a horizontal rocking crank-shaft held under tension therein, means for applying tension to said 10 rock-shaft and actuating it, holding devices in said casing for holding said rock-shaft against its tension, a trip lever for releasing said holding devices, thread supports mounted on pivoted levers above said casing, and a 15 connection between said pivoted levers and said trip lever whereby the swinging of said thread supports under any abnormal tension of the threads will operate said trip lever to set off the stop motion mechanism, substantially as set forth.

20 10. A stop motion mechanism comprising a casing on the frame of the machine, a rocking crank-shaft mounted therein under tension and operatively connected by separate 25 direct connection with the power controlling and brake mechanism, means for applying tension to said rock-shaft and actuating it, holding devices in said casing for securing said shaft under tension, a trip lever for releasing said holding devices, thread supports mounted to swivel in pivoted levers mounted above said casing, and a connection from said pivoted levers to said trip lever, substantially as set forth.

30 35 11. A stop motion mechanism for knitting machines comprising a casing, a rocking crank-shaft mounted therein under tension, means for applying tension to said rock-shaft and actuating it, holding devices in 40 said casing for securing said rock-shaft against its tension, operative connections between the cranks of said rock-shaft and the power controlling and brake mechanisms, a trip lever for releasing said holding devices, 45 pivoted levers above said holding devices, thread support mounted on pivots on said pivoted levers and connected with said trip lever, said thread supports being mounted to swivel in said levers, other thread supports on the outer end of a supporting arm to one side of said pivoted support, and means for releasing the threads from said supports when said levers tilt under strain from the thread thereon and also set off the 50 55 stop motion, substantially as set forth.

12. A stop motion mechanism for knitting machines comprising a casing mounted on the machine frame, power controlling and brake mechanism, a rocking crank-shaft mounted in said casing and operatively connected with the power controlling and brake mechanisms, means for applying tension to said rock-shaft and actuating it, holding devices for securing said shaft in a fixed position under tension, means for releasing said

holding devices comprising pivoted thread supports mounted on a part of the frame extending above said casing, said thread supports mounted to swivel in pivoted bases or levers and formed with hook-shaped upper ends, disk thread supports mounted on pivots on the outer end of a laterally extending part of the frame and connected by a connecting rod to the lower ends of said levers, said disks being provided with projecting prongs between which the threads may pass, whereby as said thread supports are tilted under any undue tension of the thread they will also swivel and at the same time rock said disks and bring the supporting prongs into a position to permit the thread to slide off said supports, and at the same time set off the stop motion mechanism, substantially as set forth.

70 75 80 85 13. In a stop motion mechanism for knitting machines, the combination of a rocking crank-shaft mounted under tension, means for applying tension to said rock-shaft and actuating it, a plurality of crank-arms on said crank-shaft, a separate connection operatively connected with the belt shifting and brake setting mechanisms respectively, devices for holding said shaft against its tension, releasing means, and means for actuating said releasing means comprising 90 95 thread supports mounted to both tilt and swivel, whereby any undue tension upon said threads will set off the stop motion mechanism and also permit the threads to slip off of said supports without breaking, 100 substantially as set forth.

14. In a stop motion mechanism for knitting machines, the combination of a rocking crank-shaft mounted under tension and operatively connected with the power controlling means and the brake mechanism, means for applying tension to said rock-shaft and actuating it, devices for holding said shaft against its tension with the parts in position to permit the machine to operate, tripping devices for releasing said holding devices, thread supports mounted on pivoted levers adapted to swing under undue tension of the thread, a lever pivoted adjacent to said pivoted levers and connected with the 105 110 115 means for setting off said holding devices, and means for regulating the tension under which said pivoted levers will operate, substantially as set forth.

120 125 130 15. In a stop motion mechanism for knitting machines, the combination of a rocking crank-shaft mounted in bearings on the frame under tension, means for applying tension to said rock-shaft and actuating it, devices for holding said rock-shaft against its tension, means for releasing said holding devices, said means comprising a pivoted actuating lever connected by a connecting rod with an angle lever above said casing, pivoted levers adjacent to said angle lever and

adapted to contact therewith carrying thread supports, said thread supports mounted to swivel in sockets in said pivoted levers, and springs for normally holding said thread supports in operative position, substantially as set forth.

16. In a stop motion mechanism for knitting machines, the combination of a rocking crank-shaft mounted under tension and connected with power controlling means and the brake mechanism, for actuating them, means for applying tension to said rock-shaft and actuating it, holding devices for securing said rock-shaft against its tension while the parts are in position for the machine to operate, means for releasing said holding device, swiveled and pivoted thread supports, a connection between said thread supports and said means for releasing the holding devices, and means for regulating the tension under which said thread supports are held in their normal positions, substantially as set forth.

17. In a stop motion mechanism for knitting machines, the combination, of a rocking crank-shaft mounted under tension and operatively connected directly by separate connections with the power controlling means and the brake mechanism for actuating the same, means for applying tension to said rock-shaft and actuating it, devices for

holding said shaft against its tension, means for releasing said holding devices, and means for operating said releasing means comprising thread supports adapted to tilt and rock to throw off the thread and at the same time actuate said releasing means under any undue tension of the thread, substantially as set forth.

18. A stop motion mechanism for knitting machines comprising an automatically operating belt shifter for the driving belt, an automatically operating brake mechanism for the driving shaft, means for holding said respective operating mechanisms locked, a single rock shaft mounted under tension and directly connected by separate connections to operate said several mechanisms, means for holding said rock shaft against its tension, means for releasing said holding means arranged to be set off by the tilt or fall of the yarn support, and said yarn supports, substantially as set forth.

In witness whereof, I have hereunto set my hand and seal at York, Pennsylvania, this twelfth day of June, A. D. nineteen hundred and nine.

IVAN W. GROTHEY. [L.S.]
